FITTING FOR METALLIC DOORS.

1,316,897.

Specification of Letters Patent. Patented Sept. 23, 1919.

Application filed July 25, 1914, Serial No. 853,120. Renewed July 19, 1919. Serial No. 312,105.

To all whom it may concern:

Be it known that I, FRANK E. HOWARD, a citizen of the United States, residing at Hartford, in the county of Hartford and State of Connecticut, have invented new and useful Improvements in Fittings for Metallic Doors, of which the following is a specification.

This invention relates to improvements in the construction of fittings for hollow metallic doors, windows, and similar structural elements, whereby the fittings are better adapted to be accurately located and firmly secured to the doors or other structures with a minimum of cutting away or mutilation of the hollow shell, in which the strength of such structures wholly or mainly resides. The improvements involve also the reinforcement of the door adjacent to and in connection with the fittings, so as to compensate for whatever cutting of the door shell may be necessary; and to strengthen and otherwise adapt the door for receiving the blows and other strains to which the fittings and the adjacent portions of the door are subjected when in use.

Figure 1 of the drawings is a sectional plan view, Fig. 2 is an edge view in section taken on the line 2—2 of Fig. 1, and Fig. 3 is a front view projected from Fig. 1, of an approved embodiment of my invention. Figs. 4 and 5 are fragmentary plan views in enlarged scale, showing details of construction and arrangement. These are sectional views, being shown in section taken on the lines 4—4 and 5—5, respectively, of Fig. 3. Fig. 6 is a sectional plan view showing a modified arrangement. Fig. 7 is an end elevation in section taken substantially like that of Fig. 2, but showing a modified form of support. Fig. 8 is a plan view, in enlarged scale, in section taken on the line 8 of Fig. 7.

The embodiment of my invention herein selected for illustration is shown in conjunction with a hollow sheet metal door of a form now coming into common use for railway coaches and other structures intended to be light, strong and fireproof. These doors are usually constructed of sheet metal bent into the form of hollow box-like rails and stiles, generally joined by glass or sheet metal panels.

For the sake of compactness, as well as for convenience, it is desirable to place the fit-

tings of such doors such as locks, latches, hinges, etc., as much as possible inside of the box-like structures of the rails and stiles. It is difficult, and in most instances inadvisable to place the working parts of these fittings permanently within the door in the process of manufacture of the door, not only because it is difficult to locate them in correct position, but because it is usually desirable to have the working fittings removable from the door, so that they may be removed and replaced at any time for examination, repairs, and renewal. It is desirable, especially in the case of articulated fittings to locate the fittings and their supporting frames or casings, not only in exact position relative to the edge or corner of the door, but also to locate them in exact relation to each other, to insure completeness and freedom of action. In the case of some articulated fittings it is important to locate the center of swinging movement of the fitting as in the case of a hinge, or in the case of the latch illustrated herein, as close as possible to an edge or a corner of the door, and to do this without unduly cutting away the door shell adjacent to the edge or corner, it being obvious that these corner angles are the strongest and stiffest portions of the shell, and should therefore as far as possible be left intact.

The fitting selected for illustration herein is a door latch adapted for the latching of swinging doors. In a latch of this character, it is desirable to have a fairly long radius of swinging movement, and also to locate the pivot or center of swinging movement reasonably close to the edge of the door, so that the latch when in its closed position will offer a more nearly direct opposition to the opening movement of the door. The latches shown herein are of the same general character and location, the modifications shown varying mainly in the form and arrangement of the supports employed inside the doors, for receiving the removable parts of the fittings, and for reinforcing the door shell.

The swinging latch 5 is pivoted at 6 within the door shell, and as nearly as is feasible or convenient to the corner of the door opposite to the side from which the latch itself extends. The latch pivot or pintle 6 is supported by posts or standards 7 which are appurtenant to the casing 8, 110

the latter being secured against the outer face of the door shell 9, with the said posts or standards projecting within the door to the opposite corner through an opening 10 in the door shell.

5 The means for operating the latch, although not essential to this invention are herein illustrated as consisting of a connecting rod 13 pivoted by one end at 14 to the latch 5 and forked at the other end as shown in Fig. 3, so as to pass on opposite sides of the knob spindle 15 operated by knobs 16 or any suitable handles or levers. A tumbler 17 carried by the latch 15 spindle engages behind the ends 18 of the bifurcated connecting rod 13 and moves that rod backward and thereby retracts the latch whenever the knobs are turned in either direction, the movement of the knobs and 20 rod being opposed by a suitable spring 19, which tends to move the parts to their latching position, and also serves to return the door knobs to their central resting position. A dead bolt 20, operated by a key through 25 the key hole 21 in any well-known way, may be employed in the casing 8.

The opening 10 in the door shell for the entrance of the latch and its supporting standards is made a suitable distance away 30 from the edge of the door, to leave a substantial portion of the corner angle of the door intact, as best shown at 25 in Fig. 5, and 26 in Fig. 7, thus leaving these corner angles much stiffer than they would be if 35 the flange portions designated by 25 and 26 were to be cut away closer to the corners of the respective doors.

In order to carry the latch pivot as far as possible toward the edge of the door, the 40 latches and their supporting standards are offset behind these uncut corner flanges 25 and 26. The opening 10 is made wide enough to admit the widest part of the offset latch and standard, and after being admitted through the opening the offset portions are moved toward the edge of the door by sliding the latch casing 8 in that direction until the latch and its standard are brought approximately against the right hand edges 45 of the corner flanges 25 and 26 of the door shell, as best shown in Figs. 5 and 6. In this way, the latch is supported in its best working position close to the edge of the door without injuriously weakening the 50 corner angles of the door shell. In the forms herein shown no openings at all are required to be made in the edge of the door, and only a few small openings are required in the sides of the door.

55 60 The latch 5 and its casing 8 after being thus slid forward toward the edge of the door to carry the offset portion of the latch behind the uncut corner angle as above described are maintained in this position 65 by means of dowel posts 27 extending from

a side plate or escutcheon or other supplemental fitting 29 situated upon the opposite side of the door shell. These dowel posts extend entirely through the door shell and the support, and enter seats 30 provided in the 70 inner surface of the latch casing 8. These dowel posts are also preferably drilled and tapped to receive holding screws 31 by means of which the latch casing 8 and the supplemental side plate 27 or other fitting 75 are clamped together on opposite sides of the door shell, thus holding the casing and fittings firmly in the exact positions determined for them.

To enable the latches or other fittings to 80 be accurately located and securely fastened to the doors, special supports for the fittings are provided, to be inserted in the doors. These supports of various forms adapted to various purposes, are preferably made by the 85 fittings manufacturer and supplied to the door maker, by whom the supports are inserted within the door shell, and secured to the inner walls thereof by welding, brazing or riveting in various well known ways. 90 Suitable jigs and templets may be employed for making the door fittings and the supports to fit each other accurately, and also for locating the supports accurately in proper position within the door shell, so 95 that the door fittings when applied to the completed door will go easily into their proper places and be secured there in proper working relation to the door and to each other. The form and size of these supports for the fittings should be adapted to 100 their respective purposes, two or three of these adaptations being illustrated herein.

The supports shown in Figs. 1 to 5 inclusive will probably be found most generally satisfactory in all cases where the door shells are made with sufficient accuracy to allow the use of this form of support. The plate portion of this support is made of a single piece of sheet metal bent into the 105 form of a deep channel. The side wings 35 and 36 of this channel form are riveted on the shouldered ends of the sleeves 37, which with the bottom portion 38 of the channel serve as braces between the two wings to 110 brace them and the sides of the door shell apart the desired distance. The holes through the sleeves 37 serve as seats for receiving the dowel posts 27, which project from the side plate or escutcheon 29 through 115 the door shell 9 and the sleeves 37 into the latch casing 8, to which they are secured by 120 screws 31.

For some purposes it may be found preferable to make the side wings of the support 125 in two separate plates 41 and 42, as shown in Fig. 6, and in that case the end or ends of one or both of the plates may be bent inwardly to form an angular reinforcement for the front corner or corners of the door 130

shell, as illustrated by the angular bend 43 of the plate 42 in Fig. 6. A further modification shown in this view is that of the latch supporting posts or standards 44 which 5 are made to fit approximately into the angle or corner at the edge of the door formed by the plates 42 and 43, thus still further reinforcing the door shell at and adjacent to that corner. The plates 41 and 42 may be provided 10 with connecting shouldered sleeves 45 which may receive dowel posts 46, as in the previous figures.

The sleeves when located as herein shown, a considerable distance away from the edge 15 of the door, may be used even when there is some variation in the thickness of the door, at its edge, due to variations in bending the door shell at the corners. Hence these sleeves may be employed in some instances 20 where the variations in the thickness of the door at its edge would not permit the use of a continuous or connected reinforcing plate like that shown in Fig. 5.

According to present methods it is found 25 difficult in practice to bend the sheet metal into the form of a door stile with sufficient accuracy to permit the use of what may be termed a solid or inflexible support, of a thickness like those illustrated in Figs. 1 to 6 inclusive. For these conditions the 30 form of reinforcement shown in Fig. 7 will be found more convenient and sufficiently firm and stable for most practical purposes. In this modification the support is made of 35 separate plates, each bent into a channel form, of a depth suitable for their various intended purposes and places. The wings or side flanges 51 of these channel shaped supports are welded, riveted, or otherwise 40 secured to the inner sides of the door shell 52, utilizing the connecting member or bottom 53 of the channel form as the bracing members between the two sides of the door shell. These channel forms may also be provided 45 with shouldered sleeves like those shown in the preceding figures, but they are preferably omitted, in which case the variations which may occur in the distance between the opposite side plates of the door 50 shell 52 may be met by suitable shaping or reshaping of the bottom members 53 of the channels, curving them more or less, as shown by dot and dash lines in Fig. 7 to shorten or lengthen them. When placed 55 fairly close to the dowel posts 55 as shown in Fig. 7 they offer a fairly direct resistance to the clamping action of the holding screws 56 while at the same time bracing directly between those opposite portions 60 of the door shell against which the latch casing 57 and the side plate 58 abut.

According to the present usual practice these hollow doors and the locks or other door fittings are made by different manufacturers. Such reinforcements as are used

for supporting the fittings are generally not supplied by the manufacturer of the fittings but are built into the door during the process of manufacturing the door, in approximate position without previously drilling or 70 otherwise providing any seats in the reinforcement for receiving the locks or other fittings. After the doors, or at least the stiles thereof, are completed, the seats for receiving the door fittings are drilled or 75 otherwise machined into the door and sometimes into the reinforcements. Thus the work and responsibility of fitting and adjusting the locks or other fittings to the door falls upon the door manufacturer, whereas 80 this work more properly comes within the province of the lock or fittings maker. This invention makes it possible for the door fittings and the supports or reinforcements to be made and adapted to each other by the 85 fittings manufacturer, and are by him furnished to the door maker, who applies them in suitable position relative to the edge or corners of the door by the use of suitable setting apparatus. To facilitate this setting, 90 and to allow for variations in the doors, which by present methods of manufacture seem unavoidable, the apertures in the door shell are made somewhat larger than the corresponding apertures in the reinforcements, as shown at 39 in Fig. 4 and at 60 in Fig. 8. This arrangement enables the door manufacturer to drill or punch these holes in the door shell while the metal is flat, before bending it into box form. The 100 oversize of the holes allows for the variations incident to the punching or drilling and bending operations upon the door shell, and the locks or other fittings may be applied to their seats in the supports with the 105 certainty of setting them exactly and uniformly into their proper positions relative to the door and to each other.

The term "removable" as herein employed refers to constructions in which the parts 110 thus designated may be bodily removed from the door without separating them from each other or otherwise disturbing their coöperative relation.

Although this invention is herein illustrated as applied to sheet metal doors and other structures which are hollow at the portions shown, it will be obvious that the invention is not in its nature limited by the kind of materials of which those structures 115 are made, or limited to the extent or degree of their hollowness, and some of the features of the invention are equally applicable to solid structures.

I claim as my invention:

1. A reinforcement for hollow shell structures consisting of sheet metal bent into channel form, the flanges of which are braced by shouldered tubular studs disposed between the flanges, the reduced ends of the 130

- 1 studs above the shoulders being extended through and riveted to the flanges, whereby the tubular studs form hollow seats opening entirely through the reinforcement.
- 5 2. The combination with a hollow shell door having openings for admitting door fittings, a support secured to the inner walls of the door shell and provided with openings corresponding with but smaller than 10 the openings in the door shell, whereby the door fittings are positioned and held by the support without filling the larger openings in the shell.
- 15 3. The combination with a hollow shell door provided with openings for admitting door fittings, a support secured to the inner wall of the door shell and having receiving seats corresponding with but smaller than the openings in the door shell, and removable door fittings provided with posts extending into said seats, through and clearing the larger openings in the door shell.
- 20 4. The combination, with a hollow shell door, of an opening in the shell, a removable door fitting having an articulated portion projecting through the opening and offset within the door shell behind the margin of said opening, and means for reinforcing the interior side of the shell adjacent to 25 said opening, and also supporting said door fittings.
- 35 5. The combination, with a hollow shell door, an opening in the shell, a removable door fitting having a base member secured against the outer side of the door shell, and an articulated member, both of said members extending into said opening, and being offset within the shell at one side of the projected area of the said opening, and a reinforcement within the shell, adjacent to said 40 opening in which the door fitting is supported.
- 45 6. The combination, with a hollow shell door, of an opening in the shell, a removable door fitting having a base secured against the outer side of the door shell, and a projecting portion extending within the door through the opening and offset at one side of said opening, an articulated member pivotally supported by said offset portion, and also extending through said opening, and reinforcing means within the shell, adjacent to said opening for receiving and supporting said door fitting.
- 55 7. The combination, with a hollow shell door, of an opening in the shell, a removable door fitting having a base member secured against the outer side of the shell, with a portion projecting within the door through 60 the opening and offset behind the margin of said opening, means within the door shell for positioning the door fitting and reinforcing the interior margin of said opening, and an articulated member also extending through said opening and pivotally sup- 65 ported by the said offset portion of said base member.
8. The combination with a hollow shell door having an opening through the shell a substantial distance from a corner portion 70 of the door, leaving the flanges of the said corner intact, and a removable door fitting secured against the outer side of the shell, and projecting into said opening substantially close to the edge of said opening, and offset within the door shell beyond the said edge toward the said corner portion.
9. The combination with a hollow shell door having an opening through the shell a substantial distance away from a corner 80 of the door, to leave the corner flanges intact, and a removable door fitting secured against the outer side of the shell and projecting through the said opening adjacent to an edge of said opening, with a portion 85 of the fitting offset toward the interior angle of the door behind the margin of said edge.
10. The combination of a hollow shell door having an opening through the shell a substantial distance from a corner portion 90 of the door, leaving the corner flanges intact, and a door fitting, secured against the outer side of the door shell adjacent to an edge of the said opening, and offset behind the edge into the interior angle of said corner, 95 and having an articulated member pivotally attached to the offset portion of the door fitting within the door shell, and extending out of the shell through the said opening.
11. The combination with a hollow shell door having an opening in its shell near the edge of the door, leaving the corner flanges of the door shell intact, a door fitting comprising an articulated member and a support therefor both extending through said 100 opening adjacent to an edge thereof, and offset within the door shell toward the edge of the door, and behind the margin of the opening, and dowel posts extending through the door to retain the fitting in its offset 105 position.
12. The combination with a hollow shell door having an opening through the shell adjacent to but away from an edge of the door leaving the corner flanges of the door shell intact, of a door fitting secured against an outer side of the door shell with a member projecting through the said opening, and offset within the shell toward the said edge of the door, and a supplemental fitting secured against another side of the door shell with a dowel extending through the door into the first named door fitting. 115
13. The combination with a hollow shell door, having an opening through the shell on one side of the door a substantial distance away from the edge of the door, to leave the corner flange of the door shell intact, and a door fitting projecting through said opening and offset within the opening 120
14. The combination with a hollow shell door, having an opening through the shell on one side of the door a substantial distance away from the edge of the door, to leave the corner flange of the door shell intact, and a door fitting projecting through said opening and offset within the opening 125
15. The combination with a hollow shell door, having an opening through the shell on one side of the door a substantial distance away from the edge of the door, to leave the corner flange of the door shell intact, and a door fitting projecting through said opening and offset within the opening 130

toward the edge of the door, and a supplemental fitting secured against the opposite side of the door shell, and having a plurality of dowel posts projecting through the door into the first named fitting to dowel the latter in its offset working position, and prevent it from turning on the door.

14. The combination with a hollow shell door having an opening through the shell on one side of the door a substantial distance away from a corner of the door to leave the corner flanges intact, of a door fitting secured against the outer side of the door with a portion projecting through said opening and offset toward the edge of the door, a latch pivoted to said offset portion, and a supplemental fitting secured against the opposite side of the door shell and having dowel posts projecting through the door into the first named fitting to dowel the latter in its offset working position.

15. The combination with a hollow shell door having an opening through the shell on one side of the door a substantial distance away from a corner of the door to leave the corner flanges intact, of a door fitting secured against the outer side of the door with a portion projecting through said opening and offset toward the edge of the door, and a supplemental fitting secured against the opposite side of the door shell and having dowel posts projecting through the door into the first named fitting, to dowel the latter in its offset working position, and means for fastening the two fittings together.

16. The combination with a hollow shell door having an opening through the shell on one side of the door a substantial distance away from a corner of the door to leave the corner flanges of the shell intact, of a door fitting secured against the outer side of the door with a portion projecting through said

opening and offset toward the interior angle of the corner, a supplemental fitting secured against the opposite side of the door shell and having dowel posts projecting through the door into the first named fitting to dowel the latter in its offset position, and means for securing the first named fitting to the said dowel posts to clamp the two fittings toward each other on opposite sides of the door.

17. The combination with a door having an opening in the side face of the door a substantial distance from the edge face of the door, a removable door fitting secured against the side face of the door, and having a projection extending into said opening, and a member pivoted within the door upon the said projection, and extending out of the door from the said opening.

18. The combination with a door having an opening in the side face of the door a substantial distance from the edge face of the door, a latch support secured to the outer side face of the door and having a projection extending into said opening, and a latch member pivoted within the door upon the said projection and extending out of the door from the said opening.

19. The combination with a door, of separable door fittings disposed on opposite sides of the door, and a post integral with and extending from one of said fittings entirely through the door into the other fitting and doweling the said fittings together.

In testimony whereof I have signed my name to this specification, in the presence of two subscribing witnesses, this 23rd day of July, 1914.

FRANK E. HOWARD.
